(57) **CLAIM**

We claim the ornamental design for a gate portion of a preform, as shown and described.

DESCRIPTION

FIG. 1 depicts a perspective view of the preform having a gate portion design according to a first embodiment;

FIG. 2 depicts a sectional view of the preform having the gate portion design of FIG. 1;

FIG. 3 depicts a perspective view of the preform having a gate portion design according to a second embodiment;

FIG. 4 depicts a sectional view of the preform having the gate portion design of FIG. 3;

FIG. 5 depicts a perspective view of the preform having a gate portion design according to a third embodiment;

FIG. 6 depicts a sectional view of the preform having the gate portion design of FIG. 5;

FIG. 7 depicts a perspective view of the preform having a gate portion design according to a fourth embodiment;

FIG. 8 depicts a sectional view of the preform having the gate portion design of FIG. 7;

FIG. 9 depicts a perspective view of the preform having a gate portion design according to a fifth embodiment; and,

FIG. 10 depicts a sectional view of the preform having the gate portion design of FIG. 9.

The broken lines in the figure drawings represent environmental structure and form no part of the claimed design.
